LAST PULLING MACHINE

Filed Aug. 24, 1931

UNITED STATES PATENT OFFICE

GEORGE A. MINER, OF MEDFORD, MASSACHUSETTS, ASSIGNOR TO UNITED SHOE MACHINERY CORPORATION, OF PATERSON, NEW JERSEY, A CORPORATION OF NEW JERSEY

LAST-PULLING MACHINE

Application filed August 24, 1931. Serial No. 559,020.

This invention relates to machines for effecting relative movement between shoes and their lasts and is herein illustrated as embodied in a machine of the type disclosed in 5 United States Letters Patent No. 1,820,952, granted September 1, 1931, upon the application of John M. Whelton and Arthur F. Pym.

Relative movement between a shoe and its last is ordinarily effected by engaging the 10 shoe frictionally with an operating member while effecting relative movement between the last on one hand and the operating member and shoe on the other hand. In the machine disclosed in the above-mentioned Letters Patent, the operating member consists of a driven roll the outer portion of which is composed of rubber; and the last is mounted upon a last pin which is supported for movement to bring the counter portion of the shoe 15 into engagement with the roll. The last pin thus serves to hold the last stationary while the roll, by frictional engagement with the counter portion of the shoe, raises the counter portion of the shoe off the last.

20 It is an object of the present invention to provide for protecting the operating member from wear and at the same time to improve its effective frictional engagement with the shoe.

25 In accordance with this object, a feature of the invention resides in the provision of an intermediate member in the form of a piece of flexible sheet material which is positioned adjacent to the operating member and which is normally stationary in the sense that it does not move continuously with the operating member, the intermediate member being constructed and arranged, when 30 pressed against the operating member by a shoe on a last, to partake of the movement of the operating member, and by frictional engagement with the shoe to move the shoe relatively to the last. In the illustrated machine the sheet material is rubber. When, as in the 35 case of the illustrated machine, the operating member is a roll, the piece of sheet material may conveniently be made by cutting a short 40 section from an inner tube of a pneumatic

tire to form a belt loosely surrounding the roll.

Marring or soiling of the shoe is prevented by avoiding relative slip between the shoe and the member which frictionally engages the shoe. Such avoidance of relative slip is accomplished by providing a shoe-engaging member which, as above stated, is normally stationary. As the intermediate or shoe-engaging member is pressed between the shoe 55 and the operating member, it begins to move with the operating member and thus moves the shoe, continuing to engage the shoe with static friction and without rubbing the shoe. The requisite tractive force between the shoe 60 and the shoe-engaging member can be developed with considerably less pressure than would be the case if the shoe were to be presented to a surface already in motion, and with a consequent saving of effort on the 65 part of the operator. Because of the comparatively light pressure between the shoe and the shoe-engaging member and because of the elimination of rubbing action upon the shoe, there is practically no tendency of the 70 shoe-engaging member to mar the surface of the shoe or to soil the shoe, as, for example, by transferring the color of one set of shoes to shoes of a different color.

75 When, as in one illustrated form of the invention, an endless belt is employed as an intermediate member, the belt is maintained in a normally stationary condition by supporting it at a point above the roll and out of driving engagement with the roll; the support, however, being constructed and arranged to permit the belt when pressed between the roll and the shoe to partake of the movement of the roll. Instead of an endless belt the intermediate member may assume the form of a depending apron suspended from a point above the level of the roll and interposed between the shoe and the roll. Such an apron may 80 also be made conveniently from the material of an inner tube.

85 Shoe-engaging members of the character above described are cheap and easy to obtain, and they function as shields to protect the surface of a more expensive roll from 90 95 100

wear. Furthermore, such a member may be reversed when its operating surface becomes worn. Also, the roll may be made of softer material than would be practicable if it were not protected by the intermediate member, conforming more effectively to the shape of the shoe and thus enabling the intermediate member to grip the shoe over a considerable area of contact. Such avoidance of excessive localized pressure between the shoe and the intermediate member insures further protection against marring or soiling the shoe. The intermediate member, being relatively thin, may advantageously be composed of tougher material than the roll.

These and other features of the invention including certain details of construction and combinations of parts will be set forth in connection with the illustrative machine and will be pointed out in the appended claims.

Referring now to the accompanying drawing,

Fig. 1 is a sectional view in side elevation of a machine for separating shoes from their lasts;

Fig. 2 is a view in front elevation of the intermediate member of the machine shown in Fig. 1; and

Fig. 3 is a sectional view in side elevation of the upper portion of the machine showing a different form of intermediate member than that illustrated in Figs. 1 and 2.

The frame 10 of the machine is hollow and has an upper compartment which houses the shoe-engaging instrumentality. This upper compartment is separated from the remaining portion of the interior of the frame 10 by a partition 12 beneath which is housed most of the driving and actuating mechanism. Journaled in the upper compartment of the frame 10 is a shaft 14 which carries a roll 16, the outer portion of which is composed of rubber. The roll 16 is driven in a clockwise direction, as viewed in Figs. 1 and 2, by gearing 18, a vertical shaft 20, gearing 22, a horizontal shaft 24, and gearing 26, from a motor 28 supported upon a bracket 30 in the lower interior portion of the frame 10.

A last jack in the form of a lever 32 is fulcrumed upon trunnion pins 34 for movement toward and away from the roll 16. The trunnion pins 34 are carried upon a sleeve 36 which is adjustably secured upon a sleeve 38 journaled upon a pin 40 secured in the front wall of the frame 10. At its upper end the lever 32 carries a last pin 42 which can be adjusted for up or down movement by means of a rack and pinion 44 controlled by a knurled head 46. Integral with the lever 32 and extending into the interior of the frame 10 through an opening in the front wall thereof is an arm 48.

A link 50 is connected at one end with the arm 48 and at the other end with a lever

52 with provision for universal movement at each of these connections. The lever 52 is pivotally mounted upon a pin 54 supported by the frame 10 and within the interior thereof. A rod 56 connects the lever 52 with a treadle 58 fulcrumed upon a pin 60 at the base of the frame 10. A spring 62 normally holds the treadle 58 in its upper position. Depression of the treadle 58 exerts a downward pull upon the rod 56, swinging the lever 52 in a counterclockwise direction, as viewed in Fig. 1, and depression of the link 50 thus swings the lever 32 in a clockwise direction toward the roll 16. A block 64 secured upon the rod 56 engages a mechanism 66 for rotating an eccentric pin 68 which extends through a slot 70 in the lever 32. The mechanism 66 and the pin 68 serve to impart a slight movement to the lever 32 in a direction lengthwise of the roll 16 for each actuation of the treadle 58, thereby varying the position of presentation of a shoe on a last mounted upon the last pin 42 and distributing the wear over the surface of the shoe-engaging member. The illustrated machine, as so far described, is identical with the machine disclosed in the above-mentioned Letters Patent No. 1,820,952, to which reference may be had for a more complete understanding of the details.

Mounted upon the top of the frame 10 is a bracket in the form of a shelf 72. The forward portion of the shelf 72 is provided with a pair of hook-shaped lugs 74 which hook under the upper forward edge of the frame 10 above the roll 16. Depending from the rear portion of the shelf 72 is a supporting lug 76 which rests upon the sloping rear surface of the frame 10. An opening 78 is provided in the rear wall of the frame 10 just above the partition 12 and below the point at which the lug 76 rests upon the rear wall. A bearing member 80 is provided in the form of a cross bar 82 having a rearward extension 84 and a pair of downwardly extending ears 86. The bearing member 80 is positioned with the cross bar 82 and the ears 86 within the upper compartment of the frame 10, with the arm 84 extending out through the opening 78 thereof. The bearing member 80 is not secured directly to any portion of the frame 10 but the ears 86 bear against the upper surface of the partition 12 and the arm 84 bears against the upper edge of the opening 78. A hook 88 is pivotally mounted in the outer extremity of the arm 84, its free end 90 engaging an opening 92 in the bracket 76. A turnbuckle 94 is provided for varying the length of the hook 88 and when tightened serves to hold the bearing member 80 in the position above described, while at the same time securing the shelf 72 rigidly to the frame 10. A pair of pins 96 which are coaxial with each other extend inwardly from the ears 86 respectively for a purpose

which will presently appear. Secured in the lugs 74 above the level of the roll 16 is a rod 98 about which travels an intermediate member in the form of a belt 100 which, in the illustrated machine, is composed of rubber and may conveniently be made from an inner tube of a pneumatic tire. The belt 100 surrounds the roll 16, and its total length is considerably greater than the circumference of the roll 16. A tubular rod 102 is journaled at its ends upon the pins 96 respectively. The belt 100 passes around the rod 102 as well as around the rod 98 and the roll 16. The rod 98 supports the major portion of the weight of the belt 100 in the vicinity of the roll 16. Before tightening the turnbuckle 94 the bearing member 80 is moved inwardly or outwardly to a position whereat most of the slack of the belt 100 is taken up by the tubular rod 102, leaving the belt 100 sufficiently loose, however, to avoid driving engagement with the roll 16. While the belt 100 in both its upper and lower run touches the roll 16, it does not, therefore, rest upon the roll 16 with sufficient force to be driven by the roll 16, a considerable portion of the weight of the belt 100 in the vicinity of the roll 16 being carried by the rod 98. When, however, a shoe S mounted upon a last L upon the last pin 42 is caused to approach the roll 16 by depression of the treadle 58, the belt 100 will be pressed by the shoe S with sufficient force against the roll 16 to cause the belt 100 to partake of the movement of the roll 16 and thereby move the shoe S relatively to the last L. The belt is thus moved progressively so that every portion of its length is utilized. In the illustrated machine the counter portion of the shoe S is caused to approach the roll 16, and the direction of movement of the roll 16 is such as to raise the counter portion of the shoe S off the last L. The inclination of the last pin 42, as shown in Fig. 1, serves to prevent the last L from being drawn off the last pin.

In order to prevent chalk from the lasts from accumulating upon the belt 100 and impairing its frictional properties, there is provided a rotary brush 110, driven by a belt 112 from the shaft 14. The brush 110 is rotated in the same direction as the roll 16 so that it will resist any tendency of the roll 16 normally to drive the belt 100. The brush 110 thus functions not only as a cleaning member but also as a brake.

In Fig. 3 is shown an alternative form of intermediate member consisting of an apron 104. In the illustrated machine the apron 104 may conveniently be made from a short length of inner tubing merely by splitting the tubing. The upper edge of the apron 104 is secured by screws 106 to clamps 108 respectively, the clamps 108 being attached to the shelf 72. The operation of the apron 104 is similar to that of the belt 100 except that instead

of moving progressively the apron 104 is raised at each operation and upon retraction of the last-holding lever 32 is allowed to fall back into its initial position by gravity. Springs or weights may be attached to the lower edge of the apron 104 to insure a more rapid return of the apron to its initial position. An apron such as apron 104 may, if desired, be used in combination with a belt such as belt 100.

Having described my invention, what I claim as new and desire to secure by Letters Patent of the United States is:—

1. A machine for effecting relative movement between a shoe and a last, comprising an operating member, means for moving said operating member, and a normally stationary piece of flexible sheet material positioned adjacent to said operating member and constructed and arranged, when pressed between said operating member and a shoe on a last, to partake of the movement of said operating member and by frictional engagement with the shoe to move the shoe relatively to the last.

2. A machine for effecting relative movement between a shoe and a last, comprising a support for the last, a driven member, said support and said driven member being constructed and arranged for relative movement of approach with respect to each other, and a normally stationary member interposed between a shoe on the last and said driven member, said normally stationary member being constructed and arranged, when pressed between the shoe and the driven member, to partake of the movement of the driven member and by frictional engagement with the shoe to move the shoe relatively to the last.

3. A machine for effecting relative movement between a shoe and a last comprising, a support for a last, a driven roll, said support and said roll being constructed and arranged for relative movement of approach with respect to each other, and a normally stationary piece of flexible sheet material interposed between a shoe on the last and said driven member, said piece of sheet material being constructed and arranged, when pressed between the shoe and the roll, to partake of the movement of the roll and by frictional engagement with the shoe to move the shoe relatively to the last.

4. A machine for effecting relative movement between a shoe and a last, comprising a driven member, a last pin mounted for movement toward said driven member, and a normally stationary piece of flexible sheet material interposed between said driven member and a shoe on a last supported by said last pin, said piece of sheet material being constructed and arranged, when pressed by the shoe against said driven member, to partake of the movement of said driven member and by frictional engagement with the

shoe to move the shoe relatively to the last.

5. A machine for effecting relative movement between a shoe and a last, comprising a driven roll, a last pin mounted for movement to cause a shoe on a last supported by the last pin to approach said roll, and a normally stationary piece of flexible sheet material interposed between said roll and the shoe, said piece of sheet material being constructed and arranged, when pressed by the shoe against said roll, to partake of the movement of said roll and by frictional engagement with the shoe to move the shoe relatively to the last.

6. A machine for effecting relative movement between a shoe and a last, comprising a driven roll, a support for a last, said support and said roll being constructed and arranged for relative movement of approach with respect to each other, a piece of flexible sheet material, and means for supporting said piece of sheet material independently of said roll with said piece of sheet material interposed between said roll and a shoe on the last on said last support, where- 25 by said piece of sheet material, when pressed between the shoe and the roll, will partake of the movement of the roll and by frictional en- gagement with the shoe will move the shoe relatively to the last.

7. A machine for effecting relative movement between a shoe and a last, comprising a driven roll, a support for a last, said support and roll being constructed and arranged for relative movement of approach with respect to each other, a piece of flexible sheet material, and means positioned above the level of said roll for suspending said piece of sheet material between said roll and a shoe on the last on said last support, said 35 piece of sheet material, when pressed between the shoe and the roll, partaking of the movement of the roll and by frictional en- gagement with the shoe moving the shoe relatively to the last.

8. A machine for effecting relative movement between a shoe and a last, comprising a driven roll, a support for a last, said support and said roll being constructed and arranged for relative movement of approach with respect to each other, an endless belt 50 of flexible sheet material loosely surrounding said roll, and a support for said belt positioned above said roll for holding said belt normally out of driving engagement with said roll, said belt support being constructed and arranged to permit said belt, when said belt is pressed between said roll and a shoe on the last on said last support, to partake of the movement of said roll and by frictional engagement with the shoe to move the shoe relatively to the last.

9. A machine for effecting relative movement between a shoe and a last, comprising a driven roll, a support for a last, said support and said roll being constructed and ar-

ranged for relative movement of approach with respect to each other, an endless belt of flexible sheet material loosely surrounding the roll and adapted, when pressed between the roll and a shoe on the last on said last support, to partake of the movement of said roll and by frictional engagement with the shoe to move the shoe relatively to the last, and a belt-cleaning member constructed and arranged to exert a braking action upon the belt to prevent the belt from being driven by the roll except when pressed between a shoe and the roll.

10. A machine for effecting relative movement between a shoe and a last, comprising a driven roll, a support for a last, said support and said roll being constructed and arranged for relative movement of approach with respect to each other, a supporting member positioned above the level of said roll, and an apron of flexible sheet material depending from said supporting member between said roll and a shoe on the last on said last support, said apron being adapted, when pressed between the shoe and the roll, to partake of the movement of the roll and by frictional engagement with the shoe to move the shoe relatively to the last.

11. A machine for effecting relative movement between a shoe and a last, comprising a support for a last, a driven member, means for effecting relative approach between said last support and said driven member, and a normally stationary sheet of rubber interposed between said driven member and a shoe on a last on said last support, said rubber sheet being constructed and arranged, when pressed between the shoe and the driven member, to partake of the movement of the driven member and by frictional engagement with the shoe to move the shoe relatively to the last.

12. A machine for separating shoes and lasts, comprising a support for a last, a driven roll, a normally stationary piece of flexible sheet material interposed between said last support and said roll, and means for causing relative movement between said last support and said roll to effect engagement between said piece of sheet material and the counter portion of a shoe on the last on said support, whereupon the piece of sheet material will be pressed between the shoe and the roll and will partake of the movement of the roll and by frictional engagement with the counter portion of the shoe will raise the counter portion of the shoe relatively to the last.

In testimony whereof I have signed my name to this specification.

GEORGE A. MINER.
